UNITED STATES PATENT OFFICE.

FRANZ LAWACZECK, OF MUNICH, GERMANY, ASSIGNOR TO WORTHINGTON PUMP AND MACHINERY CORPORATION, OF NEW YORK, N. Y., A CORPORATION OF VIRGINIA.

ROTARY AIR PUMP.

Application filed September 29, 1926. Serial No. 138,352.

The present invention relates to a rotating air-pump of the kind in which water penetrates from the outer periphery of a runner into the blading-cells and here acting as a piston drives in front of itself and thereby compresses in these blading-cells air or other gas, while during its outward flow from these blading-cells it draws after itself into the blading-cells air from the central portion of the runner.

According to the present invention a quantity of water enclosed in such a pump does not operate as hitherto simply as a pump-piston by the runner being driven externally by means of a shaft, but on the other hand the pressure-water penetrating into the blading-cells and compressing the air or the like simultaneously rotates the runner, so that the runner operates simultaneously as a turbine-wheel and as a pump-wheel. The latter is in consequence of the pressure-water which penetrates from the outer periphery, after the consumption of its energy both for driving the runner and for compressing the air, being flung outwardly in consequence of the pumping action of the runner and, in the manner otherwise known, hereby withdrawing air into the runner-cells from the central portion of the runner.

This construction has inter alia the essential advantage of considerably simplifying the machine in that external driving of the runner is altogether dispensed with. The runner is surrounded on all sides by the machine casing and is journalled therein. In this way the otherwise necessary stuffing-box for the driving shaft of the runner and obviously also the shaft itself are entirely dispensed with, whereby the otherwise unavoidable lack of tightness of, and penetration of air through, the stuffing-box are entirely avoided. For this reason the new machine is specially well adapted as a vacuum air-pump for the production of high negative pressures or vacua.

The runner preferably receives a number of admission-impacts on its periphery and it is mostly preferred that the admission openings or nozzles for the pressure-water are located in the axial direction laterally adjacent to the plane of the runner-blades so that the pressure-water penetrates at an inclination from without into the blading-cells. The water flung out by the pumping action preferably collects in spiral guiding passages

which are arranged in the plane of the runner-blades. The suction and the pressure pipes for the air or gas are preferably arranged centrally in the machine-casing and here open into a stationary distributor which is known per se and is arranged centrally in the interior of the runner.

One of the numerous possible embodiments of the invention is shown by way of example in the accompanying drawing, 65

Fig. 1 shows in its upper portion a radial section taken on the middle plane of the runner of the machine, in its left and lower quadrant a section of the supply-duct for the pressure-water and in its right and lower portion a view of the exterior of the machine casing, and

Fig. 2 is an axial section of the machine. Referring to the drawing, a runner *a* is 75 surrounded by the two parts *b*¹, *b*² of the machine-casing which are connected by bolts *b*⁴ or the like, the mounting being such that the runner *a* is journalled at *c*¹ and *c*² in the casing *b*¹ and *b*² without however there being connected to this runner *a* a shaft which extends from the casing. In the circumferential portion of the casing are provided side by side in the axial direction two ducts *d* and *e*, of which the duct *d* which is located 80 in the axial direction laterally with respect to the runner *a* is connected to the water-inlet-pipe-connection *f*, while the circumferential duct *e* which is located in the plane of the runner and is sub-divided by a series of spiral 85 tongues *e* is connected to the water-outlet-pipe-connection *g*. Leading from the water-inlet duct *d* to the blading-cells of the runner *a* are provided preferably a number of inclined ducts or nozzles *d*¹. In order to permit the water from the nozzles *d*¹ to enter laterally into the blading-cells one of the side walls *a*¹ of the runner is somewhat 90 smaller in diameter than the remainder of the runner so that the blading-cells are exposed 95 on one side of the periphery of the runner and are here covered by the casing wall *b*³ which is penetrated at a few places by the nozzles *d*¹. Between the two walls *a*¹, *a*² of the runner is arranged a series of blades *a*³ so that cells *a*⁴ are formed in the runner. 100

Centrally disposed in the runner *a* is a distributor *h* which is connected to the machine casing and is therefore stationary. Into this distributor open two pipes prefer- 110

ably located centrally in the machine casing namely, the suction-pipe i for the air or gas to be compressed, and the tube k wherefrom the compressed air issues. The suction-chambers h^1 in the distributor h are separated from the pressure-chambers h^2 by means of dividing walls h^3 . From the two chambers there extend outwardly radial passages h^4 or h^5 in such manner that the mouths of these passages are located directly in front of the inner mouths of the blading-cells of the runner a .

The mode of operation of the machine is as follows:—

At the beginning the blading-cells a^4 are filled from the suction-chamber h^1 and the passages h^4 of the distributor h with the air or gas to be compressed. Now as soon as the pressure-water penetrates in an inclined direction from without into the blading-cells a^4 by way of the duct f , the circumferential duct d and the nozzles d^1 , the runner a is set in motion in the direction of the arrow. The inner end of the blading-cell a^4' , which was originally located for example in front of a passage h^4 , is thus closed by the blocking wall h^6 , whereupon water penetrates from without through the nozzle d^1 and forces inwardly the air enclosed in the cell while compressing the same. The energy of this pressure water is consumed by this compression as well as by driving the runner a by the time the inner end of this cell a^4' is located in front of the radial passage h^5 which leads into the pressure chamber h^2 of the distributor. On further rotation of the runner a the water contained in the cell a^4' is flung outwardly by centrifugal force so that it passes into the spiral chamber e^2 of the circumferential duct e and from this into the water-outlet pipe-connection g . When the water flows out of the blading-cells a^4 the remainder of the air in them expands until the inner mouth of the blading-cells comes in front of the next radial passage h^4 , whereby the cell is again filled from within with air to be compressed.

In itself it is indifferent how often the runner receives admission-impacts by the jet of pressure-water during one revolution, or how often therefore the cycle of operations is repeated during one revolution of the runner. In the embodiment described by way of example three admission-nozzles d^1 are provided.

I claim:—

1. A rotary air pump comprising a casing, a runner having blading cells therein a distributor for the supply and discharge of air to and from the runner, means for introducing fluid under pressure to the periphery of said runner for compressing and discharging the air from the runner and means for discharging the pressure fluid from the periphery of said runner for drawing in a further supply of air to be compressed, said pressure

fluid constituting the sole means for rotating the runner.

2. A rotary air pump comprising a casing, a runner having blading cells therein, said casing and runner being concentric, a central distributor for the supply and discharge of air to and from the runner, means for introducing fluid under pressure to the periphery of said runner for compressing and discharging the air from the runner, and means for discharging the pressure fluid from the periphery of said runner for drawing in a further supply of air to be compressed, said pressure fluid constituting the sole means for rotating the runner.

3. A rotary air pump comprising a casing, a runner having blading cells mounted therein, a central distributor for the supply and discharge of air to and from the runner, a circumferential duct supplying fluid under pressure, a plurality of nozzles discharging the pressure fluid into said runner for compressing and discharging the air from the runner, and a circumferential discharge duct receiving the pressure fluid from the periphery of said runner for drawing in a further supply of air to be compressed, said pressure fluid constituting the sole means for rotating the runner.

4. A rotary air pump comprising a casing, a runner having blading cells journaled therein, a central distributor for the supply and discharge of air to and from the runner, circumferential axially displaced inlet and outlet ducts for pressure fluid, and a plurality of inlet nozzles laterally disposed with respect to the plane of said blading cells and directed towards the periphery of the runner.

5. A rotary air pump comprising a casing, a runner journaled therein having blading cells and one side wall of smaller diameter than the remainder of the runner, a central distributor for the supply and discharge of air to and from the runner, means for supplying pressure fluid to the exposed periphery of the runner blading cells for compressing and discharging the air from said runner, and means for receiving the pressure fluid discharged from the outer periphery of said runner for drawing in a further supply of air to be compressed.

6. A rotary air pump comprising a casing, a runner journaled therein having blading cells and one side wall of smaller diameter than the remainder of the runner, a central distributor for the supply and discharge of air to and from the runner, a circumferential duct for pressure fluid, a plurality of inlet nozzles connecting said duct with the exposed peripheral edge of the runner blading cells and directed towards the periphery of the runner, and a circumferential outlet duct receiving the pressure fluid discharged from the outer periphery of the runner.
